UNITED STATES PATENT OFFICE.

JOHN F. STEWARD, OF CHICAGO, ILLINOIS.

SPRING-CATCH TONGUE-SADDLE FOR HARVESTERS.

SPECIFICATION forming part of Letters Patent No. 701,099, dated May 27, 1902.

Application filed November 14, 1901. Serial No. 82,179. (No model.)

To all whom it may concern:

Be it known that I, JOHN F. STEWARD, a citizen of the United States, residing at Chicago, in the county of Cook and State of Illinois, have invented certain new and useful Improvements in a Spring-Catch Tongue-Saddle for Harvesters, of which the following is a specification, reference being had to the accompanying drawings, forming a part thereof.

My invention relates to means for securing the tongue to the divider end of the platform when the machine is mounted upon a truck for transportation upon narrow roads. Its object is to provide a catch by means of which the tongue may be readily and securely attached to the platform and which at the same time will prevent it from being worn thereby.

In the drawings, Figure 1 is a perspective view of the divider end of a grain-harvester, showing the tongue attached thereto. Fig. 2 is an end elevation of tongue-saddle. Fig. 3 is a side elevation of same.

The catch-saddle A, Figs. 1 and 2, has the body portion A', preferably formed of a single casting. It consists, chiefly, of the base-plate a, upon which it rests and by which it is secured when in use, the web a' substantially at right angles thereto, and the upper bifurcated member a². Each part of said bifurcated member is provided with the bosses a³ and a⁴. Immediately below the bosses a³ and a⁴ the web a' is provided with the bosses a⁵ and a⁶. A web connecting the boss a⁵, the web a', and the base-plate a serves to strengthen the whole. Suitable ribs extending from the bosses a³ and a⁴ to the bosses a⁵ and a⁶ serve to strengthen the parts of the bifurcated member a². On either side of the base-plate a are the posts a⁷ and a⁸, which are provided with enlarged wearing-surfaces at their top. These wearing-surfaces are in line with the bottom of the opening between the parts of the bifurcated member a², the reason for which will later be pointed out.

Extending at right angles to the web a' and on one side of the base-plate a is the rub-iron a⁸. A U-shaped bolt B is provided with the legs b and b', the leg b being somewhat longer than the leg b'. Said legs are adapted to be inserted in suitable holes in the bosses a³, a⁴, a⁵, and a⁶, respectively. On

the leg b is placed the coil-spring b², one end of which is adapted to bear against the boss a⁵ and the other against the washer b³, which is held in position by means of the spring-cotter b⁴, which passes through the leg, or other suitable means. The leg b' and the spring b² bear such a relation to each other that when the bolt B is drawn out against the action of the spring b² to the fullest extent the end of the leg b' is drawn into the boss a⁴, so that it does not cross the opening between the parts of the bifurcated member a².

In Fig. 1, C represents a harvester-platform; D, the outside divider; E, the grain-wheel, and F the draft-tongue as applied for transportation. Beneath the platform are secured the usual strengthening-angles c and c'. Secured to the tongue F at its rear end is the iron f, and at a proper distance therefrom relative to the distance between the angles c and c' is secured the catch-saddle A. The angle c is provided with a hole or slot adapted to receive the iron f. The opening between the parts of the bifurcated member a² is adapted to receive the angle c', which is provided with a hole to receive the leg b' of the U-bolt B. The angle c' rests upon the wearing-surfaces at the top of the posts a⁷. The grain-wheel E rests upon the rub-iron a⁸. In Fig. 1, however, the wheel is shown in a raised position, so that the saddle may be more readily seen.

To apply the tongue to the harvester for transportation, it is simply necessary to insert the end of the iron f in the hole or slot in the angle c, draw the U-bolt B so that the angle c' may be placed in the opening between the parts of the bifurcated member a² of the catch-saddle A, then insert the leg b' of the U-bolt B in the hole in the angle c'. The bolt is held in engagement with the angle by means of the spring b², as above described.

This catch-saddle may be used in a variety of ways. Hence I do not wish to be limited to its application to a harvester.

What I claim as my invention, and desire to secure by Letters Patent, is—

1. In a harvester, the grain-receiving platform, the said platform having the flanged bar c', means whereby it may be grasped by a latching device, a bar, as C, also secured to

the said platform and having means by which the end of the tongue may be securely connected to it, the tongue having the attachment at its rear end adapted to engage the said bar C, and also having upon it a saddle provided with a spring-latch adapted to support and engage the said bar c', substantially as described.

2. In a harvesting-machine, a latch adapted to connect one part of said machine to another part of said machine, consisting of the body A', secured to one portion of the machine, and having a rest to receive another portion of said machine to be held thereby

and having a latch consisting of the U-shaped bolt B, upon one of the legs of said U-shaped bolt the spring b², and the other leg b' of the said U-shaped bolt guided in the said body, thus forming the latch, substantially as described.

In testimony whereof I have signed my name to this specification in the presence of two subscribing witnesses.

JOHN F. STEWARD.
